POWER DRIVEN HAIR CLIPPER

Mathew Andis, Racine, Wis.

Application October 8, 1931, Serial No. 567,640

9 Claims. (Cl. 30—1)

My invention relates to improvements in power-driven, or electromagnetically operated hair clippers.

Objects of my invention are,—to improve the structure of such clippers by increasing their sensitivity, whereby the armature and clipper blade may be rendered more instantly responsive, and therefore more easily tuned to the vibrations of an alternating current; to provide means for regulating the strength of magnetic pull by variably shunting a desired portion of the lines of force; and to accomplish these improvements in a less expensive hair clipper than those of the electromagnetic type heretofore manufactured, without sacrifice of durability and with increased security against mal-adjustments by incompetent and inexperienced persons.

A further object of my invention is to provide an electromagnetic hair clipper of standardized design, in which substantially all necessary adjustments may be predetermined at the factory and the necessity for adjustment by the operator reduced substantially to the simple operation of regulating the strength of the magnetic circuit through the armature by means of an adjustable shunting bar.

In the drawings:

Figure 1 is a plan view of a hair clipper embodying my invention, with the top wall of the casing partly broken away and portions of the side walls shown in horizontal section.

Figure 2 is a view of the same in side elevation, with the side wall partially broken away and portions of the top and bottom walls shown in vertical section.

Figure 3 is a view of the armature and associated blade operating parts with the armature mounting detached.

Figure 4 is a side elevation, showing a modified form of my invention, with one side wall partially broken away as in Figure 2 but to a more limited extent.

Figure 5 is a plan view partially broken away as in Figure 1.

Figure 6 is a view of the modified armature and associated movable parts, with the mounting detached.

Like parts are identified by the same reference characters throughout the several views.

In Figures 1, 2 and 3 the casing 10 may be of any ordinary form, preferably provided with a three-pole magnet 11 having an energizing coil 12 wound upon the central pole piece or leg.

The working end of the casing is preferably provided with an adjustable mounting 13 to which

an ordinary comb plate 14 is secured as indicated at 15. The movable clipper blade 16 is mounted upon the blade 14 and provided with a longitudinally extending corrugation which forms a substantially V-shaped guide receiving groove 17 in its upper surface which receives a flat tension applying guide spring 18 having a counter corrugation which engages in the groove 17. The inner margin of this spring is secured to the adjustable head 13. These parts may also be regarded as of ordinary construction and are not claimed herein except as to the co-operative relation of the guiding means with the blade actuator now to be described.

The electro-magnet 11 is located within the casing near the end distant from the blades, this being made possible by supporting the blade actuator, including an armature in the magnetic field, from a portion of the casing between the electro-magnet and the blades whereby the actuator may be operated by the magnet as a lever of the first class. This arrangement brings the fulcrum relatively near to the blades, and emphasizes the problem of utilizing the swinging movement of the actuator for operating the blade in a straight line.

An actuator is employed for the movable blade 16, which includes an armature 20, an armature supporting arm 21 and a connector plate 22 having an extension 23, preferably non-metallic, and provided with a forked head 24 which has cylindrically rounded bearing surfaces for engagement between upstanding ears 25 connected with the movable blade 16 whereby vibratory movements of the actuator may be transmitted to reciprocate the blade 16 upon the comb plate 14. The bearings of the forked head member upon the ears 25 are substantially in the line of the axis about which the mounting 13 oscillates for the purpose of adjustment. The actuator is supported from the casing by two crossed springs 26 and 27 connected with the casing by a bracket 28 having a flange 29 to which one end of the spring 27 is secured, and a flange 30 to which an intermediate portion of the spring 26 is secured. The springs 26 and 27 are flat springs disposed in planes substantially at right angles to each other with their wider or so called flat sides substantially perpendicular to the bottom of the casing.

One end of the spring 26 is secured to a depending flange 35 carried by the connector plate 22 and its other end is secured to a shunt bar 36 which extends along the pole faces of the magnet, and is adjustable into greater or less proximity thereto by means of an adjusting screw 37 swiv-

eled to the casing and operable by means of an exterior knob as clearly shown in Figure 1.

The spring 27 connects the bracket flange 29 with the hook shaped extremity 40 of the armature supporting arm 21 whereby this arm holds the armature 20 in the magnetic field, the intensity of which is determined by the position of the shunt bar 36 as above explained.

With the construction above described, it will be obvious that the springs 26 and 27 may not only be used to support the armature but to retract it in the intervals of changing polarity when an alternating current is passed through the energizing coil of the magnet. The springs support the actuator with complete stability against any movement other than a movement in the plane in which the springs flex. And owing to the fact that the springs diverge from their crossing point toward their respective ends, the combined effect of the two springs is to provide the actuator with an axis of oscillation substantially co-incident with the crossing point of the springs. Although the axis shifts slightly during spring flexion, the stroke or oscillatory movement of the actuator is so short that the shifting movement of the axis is scarcely noticeable. The form of the actuator head 24 and its relation to the blade ears 25 is such as to allow the blade to move in a straight line upon the comb plate.

The use of the supporting springs 26 and 27 enables me to avoid the use of a pivot pin which would be necessarily small and would require lubrication to prevent rapid wear and noisy operation. It also avoids machine work, makes it possible to employ dies for cutting and shaping the parts from sheet metal and facilitates construction and assembly at minimum cost.

In the modified form of construction shown in Figures 4, 5 and 6, the armature and associated parts are substantially pivotally mounted. In this construction the case, the magnet, the blades and their supports, may be assumed to be the same as above described with reference to Figures 1, 2 and 3, but the mounting bracket 28a is preferably of a generally U-shaped form, with an intermediate portion resting upon the bottom of the casing and one upwardly extending leg 59 secured to the side wall of the casing by screws 49 engaging in threaded apertures in this leg.

The other leg 48 of the bracket is of less height, and a flat spring 26a is secured thereto and also to an adjustable shunt bar 36a having its otherwise free end connected with the casing by an adjusting screw 37a substantially as above described with reference to Figures 1, 2 and 3.

The vertically extending portion 50 of the mounting has its interior face provided with a rib 52 to which one arm of a bowed or U-shaped spring 27a is clamped by the clamping bar 53 and bolts or screws 54. The other arm of the spring 27a extends along the upper margin of the mounting wall 48 and through a slot 55 in a connector member 22a to which the armature bar 20a is secured.

The connector 22a may be made of any suitable material. If non-metallic or of soft metal, it will preferably be provided with a vertically extending groove into which a hard metal filler 60 will be pressed, said filler having a vertically extending V-shaped notch 61 into which a pivot plate or blade 62 may extend from the vertical wall 50 of the mounting bracket. This plate 62 will preferably have a knife-like edge for engagement in the V-shaped notch 61 and thus provide

a pivot bearing along a line perpendicular to the bottom of the mounting bracket and of the clipper casing. The connecting arm 23a, preferably of fiber, will be attached to the connector piece 22a as best shown in Figure 6, and the forwardly projecting end of this arm will be constructed for engagement with the movable clipper blade substantially as described with reference to Figures 1, 2 and 3.

This arm 23a will also preferably be made of non-conducting material and may be non-metallic in order to avoid rattling or squeaking at the points of its connection with the blade.

The use of this spring in combination with the line bearing obtained in the V-shaped notch 61 makes it possible to dispense with a pivot pin and provides a pressure contact bearing which will not rattle or squeak. Also, it will be obvious that there are no parts, other than the shunt bar, to be adjusted after the device leaves the factory and the shunt bar may be adjusted without opening the casing. The casing may be formed of insulating material and may be integral to such an extent that the user will have no access to the interior and will thus be prevented from tampering with the working parts. These statements are equally applicable to the structure disclosed in Figures 1, 2 and 3, my objects being attained in both forms of construction.

It will be observed that in each form of construction illustrated herein there is no positive pivotal connection of the actuator with the casing or with any fixed support associated with the casing. In both structures the actuator is supported from the casing by a resilient member which flexes to permit the movement necessary to actuate the blade, but supports the actuator against material movement in any other direction, while allowing to the actuator a slight floating movement of accommodation which permits the cutter blade to travel upon the surface of an upturned or oblique shear plate without separation from such surface and with uniform pressure thereon at all bearing portions of the blade. This is due to the fact that each spring is free to flex independently of the other in all portions between the points of its connection, and owing to the fact that these flat springs are in planes perpendicular to the bottom of the casing and the plane occupied by the top surface of the actuator member 22, it is obvious that each spring may also flex with a slight twisting action in addition to its independent horizontal flexion and thus avoid any tendency to draw the advancing end of the oscillating cutter blade away from the shear plate at the end of a stroke in opposition to the pressure of the tensioning guide spring 48 in the groove 47. The essential difference between the two forms of construction is that, in Figures 4, 5 and 6, an open bearing with an edge or line contact is substituted for the spring 26, shown in Figures 1, 2 and 3, as the means cooperative with the other spring for holding the actuator substantially to a true pivotal axis independently of a positive pivotal connection.

The non-metallic forked head in slip joint engagement with the ears on the associated blade provides a noiseless joint characterized as a slip joint connection for the reason that the sides of the head may be inserted while under compression and allowed to expand into pressure contact with the ears. The initial operation of the clipper will cause the head to slip into its proper relation to the ears, and it is thus characterized as

a slip joint connection even though no slipping movement occurs during ordinary operation of the clipper.

I claim:

- 5 1. In an electromagnetically operated hair clipper, the combination with a casing, a set of relatively fixed and movable blades, means for guiding the movable blade for straight line movement and an electromagnet for operating
10 the movable blade, of an actuator for the movable blade resiliently supported from the casing by a set of crossed flat springs which permit swinging movement about an axial line substantially perpendicular to the bottom of the casing, said point of connection being located between the blades and the magnet, and the actuator being provided with an armature in the magnetic field.

15 2. In an electromagnetically operated hair clipper, an actuator for a clipper blade having an armature at one end a blade actuating member at the other end, and intermediate laterally extending crossed supporting members of resilient material disposed obliquely to the plane in which the armature lies and substantially perpendicular to each other and to the blade.

20 3. In an electromagnetically operated hair clipper provided with a casing, an actuator for the clipping blade having an armature at one end and a blade actuating member at the other end, intermediate laterally extending flat springs oblique to the plane in which the armature lies and disposed in planes substantially perpendicular to each other and to the blade, said springs each having a fixed connection with the casing at one end and also having another portion in fixed connection with the actuating member, a shunt bar connected with one of said springs and means for adjusting the shunt bar to vary 25 the intensity of that portion of the magnetic field in which the armature lies.

40 4. In an electromagnetically operated hair clipper the combination with a supporting casing, of a set of relatively fixed and movable blades, resilient pressure applying means for the movable blade, adapted to guide it in substantially straight line shearing relation to the fixed blade, an electromagnet having a blade actuating armature, a flat spring having one end connected with the front end of the armature and another end connected with the casing at the rear of the armature connection, said spring having its wider faces in vertical planes extending obliquely to the plane of armature vibration, a connection between the armature and the movable blade, and means for resiliently modifying the movement of said connection comprising a flat spring in a plane transverse to the first mentioned spring with one end secured to said connection and the other end supported from the side of the casing at which the armature is located, whereby the connection between the armature and blade may oscillate upon a shifting pivotal axis determined by the combined effect of the crossed springs.

45 5. In an electromagnetically operated hair clipper the combination with a casing, of a set of flat springs transversely disposed with reference to each other, with their flat faces in planes perpendicular to the bottom of the casing and connected to the casing, a toothed shearing plate, a vibratory shearing blade provided with teeth adapted to reciprocate across the shear plate teeth, a blade actuator supported from the divergent ends of the crossed springs at opposite

sides of the crossing point from their casing supported ends, and electromagnetic means for oscillating the blade actuator in a direction modified by the resistance of the blade and the resilient resistance of the springs to its movement, said blade actuator having a forked head in oscillatory connection with the blade and said blade being provided with resilient pressure applying and guiding means.

5

6. In an electromagnetically operated hair clipper the combination with a supporting casing having an obliquely disposed shear plate at one end thereof and a vibratory cutter blade mounted thereon and provided with guiding and tensioning means for holding the cutter blade to the shear plate for straight line vibratory movement, of a blade actuator having crossed supporting springs of rectangular cross section connected respectively with the casing and having their wider faces disposed within a plane substantially perpendicular to the plane in which the blade actuator vibrates, and means for oscillating the blade actuator in floating movements determined by the blade and the combined action of the springs.

20

7. In an electromagnetic hair clipper provided with a casing, a relatively fixed toothed shearing comb plate and a vibratory toothed cutter blade laterally movable on said comb plate,— the combination with said cutter blade, of an oscillatory actuator member operatively connected to transmit vibratory movement to the cutter blade, and a set of crossed flat springs having their flat surfaces in planes substantially perpendicular to the upper surface of the actuator, said springs having ends respectively connected to opposite side portions of the actuator and other ends connected with the casing, and electromagnetic means for oscillating said actuating member in directions determined by the flexion of the springs.

25

8. An electromagnetically operated hair clipper comprising the combination with a casing of non-conducting material provided with a comb plate mounting, a toothed shearing comb plate secured to the mounting, a toothed vibratory cutter blade laterally reciprocable in shearing relation to the teeth of the comb plate, an electromagnet and associated vibratory armature within the casing, a connector secured to the armature and having a non-conducting portion in rocker bearing motion transmitting connection with the vibratory cutter, and a set of crossed flat springs disposed for flexion in horizontal planes and respectively connecting opposite side portions of the connector with the casing.

30

9. In an electromagnetically operated hair clipper having a casing provided at one end with an obliquely disposed shear plate, a vibratory shearing blade and tensioning means for guiding said blade in a substantially straight line along the shear plate and for holding the same to the shear plate under resilient pressure, of a blade actuator, a set of flat springs respectively connected to opposite side portions of the actuator with their flat faces in planes perpendicular to the bottom of the casing, said springs being intermediately crossed and connected with the casing at the opposite side of the crossing point from that occupied by said blade, and electromagnetic means for oscillating the blade actuator.
